(57) CLAIM

I claim the ornamental design for a body scrubber for use in a bathtub, as shown and described.

DESCRIPTION

FIG. 1 is a front, top and side perspective view of a body scrubber for use in a bathtub embodying my new design;
FIG. 2 is a rear elevational view thereof, shown in a folded position;

FIG. 3 is a top plan view of the design as shown in FIG. 2;
FIG. 4 is a bottom plan view of the design as shown in FIG. 2;
FIG. 5 is a right side elevational view of the design as shown in FIG. 2;

FIG. 6 is a left side elevational view of the design as shown in FIG. 2; and,

FIG. 7 is a front elevational view of the design as shown in FIG. 2.
